UNITED STATES PATENT OFFICE.

JOHN F. STREIB, OF AVALON, PENNSYLVANIA, ASSIGNOR TO PRESSED STEEL CAR COMPANY, OF PITTSBURGH, PENNSYLVANIA, A CORPORATION OF NEW JERSEY.

CENTER-SILL CONSTRUCTION.

1,168,918.

Specification of Letters Patent. Patented Jan. 18, 1916.

Application filed November 20, 1912. Serial No. 732,494.

To all whom it may concern:

Be it known that I, JOHN F. STREIB, a citizen of the United States, residing at No. 739 Taylor avenue, Avalon, in the county 5 of Allegheny and State of Pennsylvania, have invented certain new and useful Improvements in Center-Sill Construction, of which the following is a full, clear, and exact description, such as will enable others 10 skilled in the art to which it appertains to make and use the same, reference being had to the accompanying drawings, which illustrate the preferred form of the invention, though it is to be understood that the invention is not limited to the exact details of 15 construction shown and described, as it is obvious that various modifications thereof will occur to those skilled in the art.

An object of this invention is to provide 20 a car underframe having a center sill construction composed of two members each formed of a commercially rolled section manipulated in such a manner as to produce a maximum of strength and stiffness with 25 a minimum number of parts.

Another object of this invention is to produce a center sill construction, suitable for use in a railway car underframe, composed of two commercially rolled sections so 30 manipulated at the ends as to form extending arms laterally spaced apart, one of the arms of each member extending either from points at the bolsters or at the rear of the bolsters to the end sills, or only a sufficient 35 distance past the bolsters to form suitable supports for the ends of the separate draft sills, the other or laterally extending arms extending substantially to the bolsters and secured thereto.

The production of a single commercially 40 rolled beam having its ends so manipulated as to form laterally extending arms and the reduction in vertical depth of the end portions of such beams has already been fully 45 illustrated, described and claimed in my pending application for United States patent, Serial No. 717,465, filed August 28th, 1912, and it is, therefore, to be understood that in this application it is the intention 50 to claim only such manipulation and construction as is novel and not included in my pending application above referred to.

My invention therefore resides particularly in the manipulation of a commercially 55 rolled section in such a manner as to produce

a truss beam shallower in depth at its ends than at its intermediate portions, and having a portion of its ends manipulated so as to extend laterally from the other or straight portion, which result is obtained 60 by slitting the web of the end portions of the beam and manipulating one of such slit portions at each end of the beam in such a manner as to make it diverge from the other of such slit portions in a manner hereinafter 65 more fully described.

My invention further resides in the combination of the ends of the truss beams with the draft sills and bolsters of the underframe.

Since the details of construction of both 70 ends of the underframe embodying my invention are substantially identical, only one of such ends has been illustrated in the drawings, and it will be understood that the 75 description of one end applies equally to both.

In the drawings in which like reference 80 characters indicate like parts throughout the several figures, Figure 1 is a plan view of a railway car underframe constructed in accordance with my invention; Fig. 2 is a sectional view of the underframe, taken on line 2—2 of Fig. 1; Fig. 3 is a longitudinal section of the underframe taken on line 3—3 85 of Fig. 1; Fig. 4 is a cross section of the underframe taken on line 4—4 of Fig. 1; Fig. 5 is a cross section of the underframe taken on line 5—5 of Fig. 1 and Figs. 6 and 7 are cross sections of the underframe taken 90 on lines 6—6 and 7—7 respectively of Fig. 1.

Referring to the drawings, 1, 1 indicate the truss beams or sills preferably constructed of commercially rolled shapes or I sections having their webs disposed vertically and their flanges outstanding horizontally. The beams 1, 1 are each perforated at 2 by punching or drilling small holes in their webs at any suitable distance from the end of the beams and preferably at a point situated at or near the neutral axis of the beams. The webs of the beams are then slit at 3, as shown in Figs. 2 and 3, such slits extending from the perforations 2 to the extreme end of the beams. The end portions 4, 4 100 of each of the beams thus split are then spread apart in a horizontal plane, as indicated by 4^a and 4^b in Fig. 1, the lower portions 5, 5 of the beams thus slit remaining 105 in their original vertical plane. The upper 110

- portions 4, 4 heretofore referred to, are spread apart laterally from their original vertical plane to any suitable extent and are shortened sufficiently to contact with the inner side of the webs of the bolster members and are secured thereto by connection angles 6, thus forming very efficient diagonal braces between the center sills and bolsters. The lower portions 5 of the beams 10 when slit are then bent upwardly in a vertical plane and at an angle to the end portions 4, 4 in order to reduce the vertical distance between the horizontal planes of the outsides of the top and bottom flanges of 15 the original beams, to an extent sufficient to adapt them for suitable combination with the bolster and other members of the underframe of the car.
- 7 indicates the center brace, which is 20 shown in the form of a casting, its function being to receive the king pin and to brace at any suitable distance apart the slit ends 5, 5 of the truss beams 1, 1. This center brace 7 may be located at any suitable distance from the ends of the lower portions 25 5 of the beams, and preferably at such a distance therefrom as to make the ends of the beam, which project beyond the center casting, of sufficient length to form a splice 30 for the draft beams or sills. At the points where the center brace 7 is secured between the ends 5, 5 of the beams 1, 1 bolster members 8, 8 are secured to the portions 9, 9 of the web of the lower members 5, 5 of the 35 beams 1, 1. These bolster members can be of any suitable form or material, but preferably may be constructed of pressed steel diaphragms, as shown in the drawings. The lower portion of the center brace 7 and its 40 flange 7^a, as well as the lower flanges 10, 10 of the ends 5, 5 of the beams, are all secured together by a bolster tie plate 11, which extends across the aforesaid center brace. The upper flanges 12 of the bolster 45 diaphragms 8 are secured together by the top bolster tie plate 13.
- To the ends 5, 5 of the beams, which extend beyond the bolsters, draft sills or beams are secured, which may be of any 50 suitable length and shape. One end of each of these draft sills overlaps the ends 5, 5 of the beams and are secured thereto, and the other ends extending to and are secured to the end sill 14.
- 55 To compensate the lower portions 5, 5 of the beam for loss of strength, due to the removal in a sidewise direction of their upper flanges 15, 15 and upper portions of their webs 16, 16 and to enable them to 60 better resist any tendency to buckling under buffing shocks, angle bars 17, 17 are riveted to the webs 16, 16 of the beams near to the top flanges 15, 15 at points 18, 18. These angle bars extend from the points 18, 18 65 in substantially the same vertical plane,

until they contact with the upper portions 19, 19 of the webs 9, 9 of the lower portions 5, 5 of the beams. These angle bars 17, 17 are secured to the last referred to portions 5, 5 of the beams and may extend to 70 the ends thereof, and are secured to the bolster tie plate 13, at points 20, 20 where they pass under it and contact with its lower surface.

21 indicates the striking casting of the 75 car underframe which is secured to the end sill 14, and which may be of any suitable shape and material.

22 indicates one of the cross bearers of the underframe, which is shown of I section. 80 These cross bearers pass through perforations in the webs of the beams 1, and are secured to the webs of the beams by suitable members 23, through which the I beams are passed and secured. Continuous Z shaped 85 side sill members 24 are supported by the ends of the bolsters and cross bearers and on these sills are carried the usual side nailings stringers (not shown), though it is evident that any form of side sills or their 90 equivalent may be substituted if desired, this invention relating particularly to the double I beam center sill underframe described and its associated parts.

It is to be understood that I do not limit 95 my invention to slitting the end portion of the web of a webbed section of metal, spreading one of such slit portions apart laterally and bending upwardly the lower of such portions so slit, but it is within the principle 100 and scope of my invention to bend downwardly the upper portion of the slit end of the section, or to bend both members either upwardly or downwardly in a vertical plane, as may be found most expedient. Nor do 105 I limit my invention to spreading laterally the upper portion of the end of the beam so slit, the lower portion remaining in its original vertical plane; but, it is within the principle and scope of my invention to 110 spread laterally the lower portion of the end of the beam, the upper portion remaining in its original vertical plane.

I am aware that it is old in the art to effect a reduction in the depth of a webbed 115 metal beam by cutting away a portion of the web at the end of the beam, and bending toward each other in their original vertical plane the edges of the web conterminous with such cut away portion, and also by 120 displacing a portion of the web at the ends of the beam and simultaneously bending the longitudinal edges of the beam toward each other in the same vertical plane, and this application is therefore intended to cover only 125 so much of the disclosure made herein as is covered by the claims.

What I claim is:

1. In a car underframe, a center sill consisting of two webbed metal longitudinal 130

- members, each member having the end of its web slit, one portion of such slit end being displaced from its original vertical plane and away from the other portion. 65
- 5 2. In a car underframe, a center sill consisting of two webbed metal longitudinal members, each member having the ends of its web slit, one portion of each slit end being displaced from its original vertical plane 70 upwardly in a vertical direction and being out of contact with the other portion of said end.
- 10 3. In a car underframe, a center sill consisting of two webbed metal longitudinal members, having their ends slit, portions of 75 such ends being displaced laterally in opposite directions.
- 20 4. In a car underframe, a center sill consisting of two webbed metal longitudinal members, having the ends of their webs slit, portions of such ends being displaced from their original vertical plane in opposite directions. 80
- 25 5. In a car underframe, a center sill consisting of two webbed metal longitudinal members, each member having the ends of its web slit, one portion of each slit end being spread away from the remaining portion 85 of said end.
- 30 6. In a car underframe, a center sill consisting of two webbed metal longitudinal members, having their ends slit, portions of such slit ends being spread away from the remaining portions and in opposite directions to each other. 90
- 35 7. In a car underframe, a center sill consisting of two webbed metal longitudinal members, each member having the end of its web slit, one portion of such end being displaced vertically and the other portion being 95 displaced laterally, said portions being out of contact with each other. 100
- 40 8. In a car underframe, a center sill consisting of two webbed metal longitudinal members, having their ends slit, portions of such ends being displaced laterally in different directions. 105
- 45 9. In a car underframe, a center sill construction consisting of two webbed metal longitudinal members, having the ends of their webs slit, one portion of the end of each member being displaced in its original vertical plane and the other portion of each member being displaced from its original 110 vertical plane.
- 50 55 10. In a car underframe, a center sill consisting of two commercially rolled beams having their ends slit, portions of said slit ends being displaced laterally in different directions. 115
- 55 60 11. In a car underframe, a center sill consisting of two commercially rolled beams having their ends slit, portions of such ends being displaced vertically and laterally, said 120 portions being vertically and laterally displaced portions of each beam being out of contact with each other.
12. In a car underframe, a center sill consisting of two commercially rolled beams having the ends of their webs slit, one portion of the end of each beam being displaced 125 upwardly in a vertical direction and being out of contact with the other portion of said end.
13. In a car underframe, a center sill consisting of two commercially rolled beams having the ends of their webs slit, one portion of each of said ends being displaced laterally from its original vertical plane and away from the other end portion of said beam. 80
14. In a car underframe, a center sill consisting of two commercially rolled beams, having the ends of their webs slit, portions of such ends being displaced from their original vertical plane and in opposite directions. 85
15. In a car underframe, a center sill consisting of two commercially rolled beams, having the ends of their webs slit, one portion of the end of each beam being spread away from the other portion and away from its original vertical plane. 90
16. In a car underframe, a center sill consisting of two commercially rolled beams, having the ends of their webs slit, one portion of one of said ends being displaced in an opposite direction to that of a corresponding portion of the other of said ends. 95
17. In a car underframe, a center sill consisting of two commercially rolled beams having the ends of their webs slit, one portion of one of such slit ends being displaced vertically and the other portion being displaced laterally, said portions being out of contact with each other. 100
18. In a car underframe, a center sill consisting of two commercially rolled beams having their ends slit, portions of such ends being so displaced as to effect a reduction in depth and an increase in width of the end of the center sill, said portions being out of contact with each other. 110
19. In a car underframe, a center sill consisting of two commercially rolled beams, each having integral diverging ends spaced apart, one of said ends being displaced from its original vertical plane. 115
20. In a car underframe, a center sill consisting of two commercially rolled beams having integral laterally diverging ends spaced apart, one portion of the end of each of said beams being displaced from its original vertical plane. 120
21. In a car underframe, a center sill comprising two commercially rolled beams having integral bifurcated ends spaced apart, one portion of the end of each beam being displaced from its original vertical plane. 125

22. In a car underframe, a center sill consisting of two commercially rolled beams having integral laterally bifurcated ends spaced apart, one portion of the end of each beam being displaced from its original vertical plane. 65
23. In a car underframe, a center sill consisting of two commercially rolled beams having integral bifurcated ends spaced apart, one portion of the end of each beam being displaced from its original vertical plane, and draft sills secured to the other portions of the ends of said beams. 70
- 10 24. In a car underframe, a center sill consisting of two commercially rolled beams having integral diverging end portions displaced from their original vertical planes and portions remaining in their original vertical planes and draft sills secured to said 75 last mentioned portions. 75
- 15 25. In a car underframe, a center sill consisting of two commercially rolled beams having integral laterally diverging end portions displaced from their original vertical 80 planes and straight portions, and draft sills secured to said straight portions. 80
- 20 26. In a car underframe, a center sill consisting of two commercially rolled beams having horizontally divided end web portions and draft sills, the upper of said end portions being spaced apart and the other of said end portions connected to said draft 85 sills. 90
- 25 27. In a car underframe, a center sill consisting of two commercially rolled beams having their ends slit, portions of such slit 95 ends being displaced vertically relative to the other portions of said ends whereby the end of the center sill is reduced in height 95 as its extremity is approached, said portions being out of contact with each other. 100
- 30 28. In a car underframe, a bolster having top and bottom cover plates, a center sill consisting of two commercially rolled beams 105 having their ends slit, portions of such ends extending through said bolster, the other portions of said ends terminating at said bolster and connected therewith, a bolster center brace between and secured to said 110 center brace between and secured to said first mentioned portions and to one of said cover plates, and a draft sill secured to each of said first mentioned portions. 115
- 35 29. In a car underframe, a bolster, draft sills, a center sill consisting of two commercially rolled shapes, both having integral bifurcated ends, portions of said ends being displaced from their original vertical planes, spaced apart, and connected with said bolster. 120
- 40 30. In a car underframe, the combination with a bolster, of a center sill consisting of two commercially rolled beams formed with integral diverging end portions, portions of said ends being displaced from their 125 original vertical planes and connected to 65 said bolster, and draft sills secured to the remaining portions of said ends. 70
31. In a car underframe, the combination with the bolster, and center sill members constructed of commercially rolled beams, 70 of diagonal braces integral with said center sill members and terminating at said bolster. 75
32. The combination with a bolster, of a center sill formed of commercially rolled beams having integral brace members terminating at said bolster. 75
33. The combination with a center sill formed of webbed metal, of a laterally extending diagonal brace member integral therewith, formed by slitting the end of 80 said sill and displacing one portion only of such slit end. 80
34. In a car underframe, a center sill consisting of two commercially rolled longitudinal members having the ends of their webs slit, the upper portions of such ends diverging outwardly and the lower portions being displaced vertically. 85
35. In a car underframe, a center sill consisting of two commercially rolled longitudinal members having the ends of their webs slit, the upper portions of such slit 90 ends diverging in opposite directions and the lower portions being displaced vertically in an upward direction. 95
36. In a car underframe, a center sill consisting of two commercially rolled beams having their ends slit, one portion of each of said ends being displaced from its original vertical plane to form a diagonal brace. 100
37. In a car underframe, a bolster, a center sill consisting of two webbed metal longitudinal members, portions of the ends of said longitudinal members extending laterally and terminating at the bolster, the other portions passing through said bolster. 105
38. In a car underframe, a bolster, a center sill consisting of two webbed metal longitudinal members, and laterally extending diagonal braces integral with said longitudinal members secured to and terminating at said bolster. 110
39. A truss beam consisting of a section of webbed metal having its end slit, one portion only of such end being displaced laterally to increase the width of said beam at its end, the other portion being displaced in its original vertical plane to decrease the height of said beam at its end. 115
40. A truss beam consisting of a section of webbed metal having its end slit, one portion only of such end being bent and spaced apart from the other portion to increase the width of the end of said beam. 120
41. In a car underframe, a bolster, draft 125 sills and a center sill comprising a pair of spaced members having their ends slit, one portion of the end of each member being

bent laterally and secured to said bolster, and the other portion of the end of each member being bent vertically and connected with one of said draft sills.

5 42. A truss beam consisting of a section of webbed metal having the end portion of its web slit, one portion of such slit end being displaced in its original vertical plane and the other portion being displaced from
10 its original vertical plane and a strength-

ening member secured to said first mentioned portion adapted to compensate for the displacement of the second mentioned portion.

In testimony whereof I affix my signature 15
in presence of two witnesses.

JOHN F. STREIB.
